CANDLE MANUFACTURE

August French, Hammond, Ind., assignor to
Standard Oil Company, Chicago, Ill., a corpora-
tion of Indiana

Application October 28, 1947, Serial No. 782,517

4 Claims. (Cl. 18—27)

1

This invention relates to a method and apparatus for making candles and particularly it relates to a method of making candles from paraffin wax compositions by the so-called "hand-dipped" method. The invention also relates to a method and apparatus for impregnating candlewick with wax for waxing tapers. One object of the invention is to provide a method and apparatus for making waxed tapers more rapidly, economically and continuously without producing distortion and irregularity of the taper.

Another object of the invention is to produce dipped candles more rapidly than has been possible heretofore without encountering distortion or warping of the candles. It is also an object of the invention to provide a rack for dipping candles which will hold the candles in perfect alignment to prevent loss of candles as a result of shifting or distortion while dipping or cooling. Other objects of the invention will become apparent from the following description thereof.

In making dipped candles heretofore, it has been the practice to attach a number of wicks to a rack and lower them into a bath of melted wax. The wax for this purpose is usually mainly paraffin, for example 125 to 135° F. melting point paraffin, generally modified with stearic acid, dye, etc. After dipping the wicks, they are withdrawn from the wax and cooled until solidified. In this operation, a certain amount of tangling occurs which must be corrected by the handwork of the operator. After solidifying, the operation is repeated until the desired thickness of the candle body is obtained. This may require about 25 to 30 dips for the ordinary "dinner taper." It is generally customary to build the body of the candle by dipping in wax of one composition and then finish the candle by a final dip in wax of another composition and/or color, the last operation being called a surface dip. The candles, suspended by their wicks, are then removed from the rack, the butts are trimmed and shaped and the finished candles are ready for packing and shipping. Trimming and shaping of the candle butts may be done before the final or surface dip, for the sake of a uniform pleasing appearance.

One difficulty encountered in this process has been that considerable time is required for solidification of the wax after each dip because of the need for dissipating the very substantial amount

of heat of crystallization while the wax congeals. Attempts have been made to speed up the cooling operation by blowing a current of cool air over the candles, by air-conditioning, etc., but the resulting irregular cooling produces an undesirable warping of the candles, which largely increases the number of rejected candles, greatly increasing the cost of the process. It has also been suggested heretofore that rapid cooling be effected by immersing the candles in a bath of cool water after each dip, but the adherence of water to the candles has produced unsatisfactory candles because drops of water adhere to the surface and become occluded in the candles between the wax layers, giving them an irregular, displeasing appearance and causing them to burn badly with sputtering.

I have now discovered that this difficulty with water cooling of candles between dips can be successfully overcome if there is added to the water a substance having the effect of reducing the surface tension of the water. For this purpose I prefer to use those substances known as wetting agents, examples being the sulfonated alkyl benzenes and naphthalenes, the sulfuric acid esters of higher alcohols, such as lauryl alcohol, and the long-chain aliphatic sulfonic acids. Generally the alkali metal salts of the above acids are employed, e. g. lithium, sodium or potassium salts. I may also employ such surface-tension lowering agents as sulfonated castor oil soap and the fatty acid soaps such as sodium oleate, sodium stearate, etc. Another class of very useful wetting agents for my purpose includes the alkyl sulfosuccinic esters, particularly sodium or potassium dioctyl sulfosuccinic ester. The amounts of wetting agent required for the purpose are very small, usually of the order of .01 to 1%, depending on the particular agent employed. I have found that it is desirable to employ sufficient surface-tension reducing agent to reduce the surface tension below about 40 dynes per centimeter. The interfacial tension between oil and water is even more indicative of the facility with which the water will disappear from the wax surface. I have found that water having a surface tension below about 40 or an interfacial tension below about 10 dynes per centimeter will not produce droplets on the surface of warm wax candles but will flatten out and substantially all leave the candle

2

when the latter is withdrawn from the cooling water bath. Any residual film of water left on the candle almost instantly evaporates and this can be hastened by ventilating with a current of air, if desired, without any hazard of warping as in the case where the candles are soft and insufficiently cooled. The following table shows the effect of three common wetting agents on surface and interfacial tension:

Concentration, Wt. Per Cent in Water	Surface Tension, Dynes/Cm.						Interfacial Tension with White Mineral Oil, Dynes/Cm.					
	0.00	0.025	0.05	0.10	0.20	1.00	0.00	0.025	0.05	0.10	0.20	1.00

² Crude lauryl alcohol sulfate (Draft).

³ Coconut fatty acid monoglyceride sulfate (Vel).

The invention is illustrated by drawings which show schematically in Figure 1 an apparatus for impregnating the candlewick with wax in making tapers.

Figure 2 is a modified form of cooling bath for the wick-treating operation shown in Figure 1;

Figure 3 shows an apparatus for dipping candles; and

Figure 4 is a candle rack of special design suitable for use with the apparatus shown in Figure 3.

Referring to Figure 1, a supply of candlewick 10, usually made of braided cotton, is withdrawn from spool 11 and passes over sheave 12 downward into the wax bath 13, where it passes under sheave 14 and thence upward over sheave 15, excess wax being removed from the wick by passing it thru a hole of suitable size in wiper plate 16. Other means for removing excess melted wax such as doctor blades, etc., may be employed, if desired. The wax in bath 13 is kept melted at the desired temperature by steam jacket 17 while make-up wax is supplied by inlet 18.

The impregnated wick at 19 next enters the open end of water-cooling tube or channel 20. The cooling channel 20, preferably can be a straight pipe of sufficient diameter to permit the passage of the wick therethru without touching the walls. It should be of sufficient length to provide the desired amount of cooling, depending on the rate of passage of the wick therethru. Ordinarily about one to ten seconds is adequate. Cooling water is supplied by line 21 and the wetting agent, in relatively dilute solution, in supply tank 22, is introduced by proportioning pump 23 and line 24. The warm water is discarded at weir 25 into catch basin 26 leading to a suitable waste line. If desired, the water may be recycled thru a cooling pond or other cooling system.

The treated wick or taper leaves the cooling tube 20 thru a suitable orifice 27 in one end and thence passes to reel 28, where it is wound up until ready for use. If desired, a jet of air may be caused to impinge on the wick at 29 to assist in eliminating any water carried as a film on the wick. Orifice 27 may be a punctured rubber diaphragm or other suitable elastic packing which will largely prevent the escape of water from the cooling tube 20, altho little tendency to escape is encountered because of the absence of any appreciable pressure. Reel 28 may be driven by a dynamometer or direct current motor

30 provided with suitable resistance to regulate the amount of torque, so that the tension on the wick can be closely controlled as it passes thru the cooling bath in pipe 20. In this way all the wick fibers are properly tensioned in the taper before the wax solidifies and holds them in place.

Instead of the cooling pipe 20, I may employ the apparatus shown in Figure 2 in which the wick, impregnated with melted wax from the bath

13 passes over sheaves 32 and 33, thence downward into cooling water bath 34 where the wick 25 passes under and over pulleys or grooved sheaves 35 and 36. These sheaves 35 and 36 can be provided with a plurality of grooves so that the wick can be passed over them as many times as desired in order to increase the length of travel 30 beneath the water surface and provide the desired amount of cooling time. By reversing the direction of travel of the wick over sheaves 35 and 36, as indicated, all sides of the wick come in contact with the grooved surfaces and receive a 35 uniform calendering, giving the resulting wax taper a particularly smooth surface suitable for use in candle manufacture. From the cooling bath 34, the wick passes over sheave 37 and thence to reel 38 as hereinabove described. Cooling water and wetting agent are supplied to the bath 34 by lines 39 and 40, respectively, the warm water overflowing at 41.

Referring now to Figure 3, which illustrates a machine for making dipped candles, a suitable rack 45 is suspended by cable 46 from pulley 47. At the beginning of the operation there is attached to the rack by numerous clips or hooks, not shown, a large number of candlewicks or rather tapers cut to approximately the length of the candles which it is desired to make, for example 8 inch, 10 inch, 14 inch, etc. It is preferred to use the precoated wicks or tapers made as just described hereinabove. The wicks hang straight down and are built up by repeated applications of wax to form the candles 48 illustrated. Numerous arrangements of machines may be employed for alternately dipping the candles in melted wax and then cold water containing a wetting agent. In one arrangement, 60 the number of wax baths and water baths are placed alternately in a circle and a swinging arm supports the cable 46 and pulley 47, so that the rack can be lowered manually into the wax and water baths alternately passing around the circle 65 until the candles are built up to the desired thickness. The apparatus of the drawing shows only one wax bath 49 which can be moved to one side to permit cooling the candles by dipping them in water bath 50.

70 The apparatus illustrated is fully automatic, the power for its operation being derived from rotating gear wheel 51. The wheel is connected thru crank 52 and connecting arm 53 to the oscillating table 54 supporting the water and wax baths. By supporting the table on pivoted legs

55, it is made to remain in either of two extreme positions for a sufficient time to permit lowering and raising the candle rack into each bath alternately. The positions can be accurately determined by adjustable stops not shown in the drawing. By allowing the crank pin 52 freedom to move in a slot 56 in connecting arms 53, an irregular movement of the table is obtained without altering the constant revolving movement of the wheel 51. Shock absorber 57 provides a smoothly decelerated movement of the table 54 into each extreme position before rack 45 is lowered.

After rack 45 has been immersed in each bath, a rack of gear teeth 58 on wheel 51 engages windlass gear 59 and causes the cable 46 to be wound up, drawing it over pulleys 60 and 47 and raising the candle rack 45 out of the bath. As soon as the candles have cleared the top of the wax container, the crank pin 52 engages the end of slot 56 and sets table 54 in motion, shifting it to the opposite position and bringing the other bath in position below the candle rack. When that has occurred, the gear rack 58 passes out of engagement with the windlass gear 59, releasing the tension on cable 46. The weight of the candle rack 45 thereupon unwinds the cable from the windlass 59, a suitable braking device or shock absorber, not shown, being provided to control the speed of descent of the candles. The candle rack is then raised again from the bath by the gear rack 61 engaging windlass gear 59 as hereinabove described. Cool water having its surface tension controlled as hereinabove described by the addition of a wetting agent is supplied by line 62 to water bath 50, the warm water being discharged by line 63. Flexible connections may be provided to permit free movement of the water bath, with table 54 as just described. Heat for maintaining the wax in 49 in melted condition can be supplied by a steam coil, a steam jacket, or by electrical heating means supplied by power thru line 64. It is desired to control the temperature of the wax in the dipping bath within rather narrow limits to regulate the deposition of wax on the candles. Ordinarily a bath temperature within the range defined by the melting point of the wax and a temperature about 15° F. thereabove is satisfactory. It is likewise desirable to control the temperature of the water bath within the range of about 5° F. below the wax melting point down to about 35° F. therebelow. Colder water can be employed to obtain rapid cooling but some danger of cracking the wax coating is encountered if too rapid chilling of the wax on the candle is obtained. The lower the temperature of the cooling water employed the thicker the deposit of wax which can be obtained on the following dip in the wax bath. The thickness of the deposit is also increased somewhat by the length of time the candles are allowed to remain in the water bath, inasmuch as more heat is thereby removed from them and a correspondingly greater amount of wax will freeze on the candle surfaces during the next dip.

By employing cooling water containing sufficient surface-tension reducing agent to maintain the surface tension below about 40 dynes per centimeter, the candles are withdrawn from the water bath substantially free from droplets of water and any thin film of water on their surfaces is rapidly evaporated before the candles enter the wax bath on the following dip. In order to build up the candle stock from the wick to the finished candle there is usually required

only from 10 to 15 dips, owing to the lower temperature attainable with water chilling using wetting agent. In fact, the more efficient cooling obtainable permits two or more wax dips for each water dip, by some modification of the dipping machine. By using the automatic dipping machine just described, hand labor is almost entirely eliminated from the operation until the candles are complete. I also contemplate employing a tensiometer device 65 in cable line 46 which with switch 66 controlling the power to drive wheel 51 automatically stops the operation of the machine when the weight of wax built up on the candles reaches a predetermined amount. A new rack of candle wicks is then substituted by the operator for rack 45 and the candles are then finished and removed from the rack as hereinabove described.

Inasmuch as the candles have a lower density than water, I employ guides in the water bath 50 to prevent them from tangling and colliding with each other during the water-cooling operation. The use of guides, however, requires that the candles be spaced on the rack a greater distance apart than would otherwise be necessary, thus reducing the number of candles which can be placed on the rack and manufactured in a single cycle of dipping operations. In order to overcome this disadvantage, I may use a rack similar to that shown in Figure 4 in which the candlewicks are held taut from top to bottom by stringing them in a wire cage. The cage 70, supported by eyelet 71, is wound of wire of sufficient stiffness to adequately support the candles and hold them in position. For this purpose, a wire of about #6 to #9 B. & S. gage is generally satisfactory. Accumulation of wax on the cage is prevented by electrically heating the cage which may be done either by resistance or induction. If the resistance method is used the cage is wound of one continuous wire as shown in the drawing, forming a continuous electrical path from one end 72 to the other end 73. Suitable electric connection, not shown, is then made to the ends 45 of the wire and, for convenience, the flexible lead connection may pass upwardly over pulley 47 along with the cable 46. A constant current of electricity may be passed thru the cage during the entire dipping operation or, by means of an automatic switch, the current may be turned on only during the time the cage is in the wax bath or just entering it, thereby heating the wire to sufficient temperature to prevent wax freezing on the cage beyond a very thin film. Metal wick hooks 74 attached to the cross wires of the cage are provided for stringing the wicks, and considerable operating time is saved by stringing the cage with one continuous wick 75, as indicated in the drawing. The use of water for cooling the dipped candles makes it possible to place the wicks quite close together, just far enough apart so that the finished candles do not touch, as it is not necessary to provide large air spaces between the candles for cooling them.

65 If induction heating of the candle rack is employed, it can conveniently be accomplished by an induction coil either surrounding the wax bath, within the wax bath, or above the wax bath. In the latter case, the rack is given a preliminary heating on passing thru the induction coil so that the cage enters the melted wax at a temperature not substantially below the wax temperature, thereby collecting substantially no wax in the dipping operation, whereas the wicks and candles, being non-conducting, receive no heat from

the induction coil and enter the wax bath cold. As a result, only the candles build up a coating of wax during the dipping step. The wick which passes laterally between the candles, particularly at the bottom, can be prevented from accumulating wax by passing it beside and in contact with a wire or other metal conductor connected to the adjoining wick hooks. When employing induction heating, the rack is constructed of metal formed to provide a continuous electrical path and an electric field of 110 to 10,000 cycles can be used as is well known in this art.

While I have described my invention giving certain specific embodiments thereof, I do not intend that it be limited thereby except as described in the following claims.

I claim:

1. The method of making dipped candles which comprises alternately dipping a candlewick in a bath of melted paraffin wax and a bath of cool water, said water containing a wetting agent in an amount sufficient to reduce the surface tension of the water to less than about 40 dynes per square centimeter, withdrawing the wax-coated candlewick from said water of low surface tension without adhering water droplets and continuing said alternate dipping in wax and water until said candle is built up to the desired thickness by deposition of wax layers thereon.

2. The method of claim 1 wherein said wetting agent is an alkali metal salt of an acid selected from the class consisting of alkyl benzene sulfonic acids, alkyl naphthalene sulfonic acids, lauroyl sulfate, sulfonated higher fatty acids, and the dialkyl esters of sulfosuccinic acid.

3. The method of preparing a wax taper which comprises continuously passing a fibrous wick thru a bath of melted paraffin wax, thereby impregnating it with said wax, wiping excess wax from said wick, and thereafter passing said wick with adhering wax thru a bath of cool water while

maintaining it under tension, thereby solidifying said wax on said wick, adding a wetting agent to the water in said bath in an amount sufficient to reduce the surface tension below about 40 dynes per square centimeter, thereby preventing adherence of water to said wick, and removing said wick from said water bath.

4. In the method of making dipped candles wherein a suitable wick is dipped in a bath of melted paraffin wax and then withdrawn to cool the layer of deposited wax and this operation is repeated until a candle of the desired diameter is obtained, the improvement comprising accelerating the cooling of said candle during the period between dips by immersing it in a bath of water maintained at a temperature below the melting point of the wax, the water in said bath containing a wetting agent to prevent adherence of water droplets to the surface of said candle, the amount of said wetting agent being sufficient to reduce the surface tension of the water in said bath below about 40 dynes per square centimeter.
